UNITED STATES PATENT OFFICE

2,652,888

BURNER AND IGNITER STRUCTURE

George W. Allen, Indianapolis, Ind., and Vernon N. Tramontini, Los Angeles, Calif., assignors to Stewart-Warner Corporation, Chicago, Ill., a corporation of Virginia

Original application June 14, 1946, Serial No. 676,776, now Patent No. 2,507,081, dated May 9, 1950. Divided and this application February 25, 1948, Serial No. 10,624

3 Claims. (Cl. 158—28)

1

The present invention relates to heaters generally and more especially to a burner for the sealed type of internal combustion heater designed for use in aircraft, small boats, automobiles, and the like. The present application is a division of our copending application Serial No. 676,776, now Patent No. 2,507,081.

The structure shown and described herein is particularly intended for use in automobiles, and one object of the invention is to provide a burner for a heater of compact form having its essential parts closely associated in a single assembly adapted to be readily installed, preferably under the engine hood of the vehicle.

Another object of the invention is to provide a structure for the purpose indicated, so designed as to be economical to manufacture with the parts arranged conveniently for making welded joints where gas-tight connections are important.

It is also an object of the invention to provide an internal combustion heater in which the pipe through which air is supplied for combustion passes through the combustion chamber for pre-heating the air, and in which the air is discharged from said pipe into a partitioned portion of a burner space to insure thorough admixture of the air with the vaporized liquid fuel.

More specifically it is an object of the invention to provide an internal combustion heater liquid fuel burner having improved starting and operating characteristics, which operates efficiently and reliably throughout a wide range of heat output and which can be manufactured in production quantities at low cost.

Other objects and advantages, including specific features of construction designed to facilitate economical manufacture, will appear more fully from the following description taken in connection with the drawings, in which:

Fig. 1 is a longitudinal vertical sectional view of a heater embodying this invention except that a portion of one end of the heater is left in elevation and adjacent portions are shown broken away to illustrate certain details of the structure;

Fig. 2 is a horizontal sectional view of a portion of the heater taken as indicated at line 2—2 of Fig. 1; and

Fig. 3 is a fragmentary detail sectional view taken as indicated along the line 3—3 of Fig. 1.

As seen in Fig. 1, the heater to which this invention relates includes an outer cylindrical casing 10 upon which there is mounted a blower, not shown, for furnishing air for combustion to the heater. Leading from the blower there

is shown an air pipe 14 bent to enter the interior of the heater through an opening in the casing 10, while an exhaust pipe 24 for products of combustion extends from the lower portion of the casing.

The interior structure comprises a plurality of coaxially disposed cylinders or sleeves. The innermost cylinder 26 forms the combustion chamber of the heater, and the burner mounted at one end of this cylinder includes a frustoconical shell 28 having at its base or larger end a cylindrical flange which is fitted into the end of the cylinder 26 and closed by a flanged end wall 30. The overlapping flanges of the members 28 and 30 and the cylinder 26 thus terminate substantially in a plane whereby the closely fitting ends may be easily welded together. A small chamber or pocket 32 is secured in a flanged opening in the end wall 30 and supports the electrically energized igniter which includes a tubular casing 34 open at one end, with a heater coil 36 of resistance wire arranged coaxially therein. The igniter tube 34 has its axis horizontally disposed in the pocket 32 so that liquid fuel fed from the valve device through a feed pipe 38 flows or drips downwardly on to the upper side of the hot tube 34 and a considerable portion of the fuel is thus vaporized. The remainder flows around the surface of the igniter tube 34 on to an absorbent mat or wick 40 composed of fine wire in woven or braided form so that the liquid entrapped therein is readily vaporized by heat radiated from the igniter and from the burning fuel in adjacent portions of the burner. Baffles 33, extending from the side walls of the pocket 32, serve to hold the mat 40 in place, while permitting any excess of unvaporized fuel to flow between them along the bottom of the pocket 32 and into the adjacent part of the burner shell 28.

The air for combustion flows through the curved pipe 14 which enters the outer casing 10 as already described, and extends through the coaxial cylindrical elements of the heater for discharging air into the frustoconical shell 28. A portion 14a extends horizontally within the combustion chamber 26 toward the burner and terminates in an elbow 14b, which discharges downwardly just below the horizontal plane of the axis of the burner shell 28. The pocket 32, in which the liquid fuel is vaporized, is also located below this axis, and opposite said pocket 32 the conical burner shell 28 is provided with a vertically disposed baffle wall 50 which is of semicircular outline as seen in Fig. 3, with its

straight upper edge located substantially at the axis of the shell 28. This upper edge of the baffle 50 is just above the discharge opening of the elbow 14b and the elbow is located against the curved wall of the shell 28 so that air is discharged from the elbow in substantially tangential relation to this curved wall and downwardly adjacent the open side of the pocket 32. This insures that the vaporized fuel will be picked up by the warm air issuing from the elbow 14b and will become thoroughly intermixed therewith as the air sweeps around the interior of the frustoconical shell 28; and any liquid fuel which may flow from the pocket 32 into the lowest part of the shell 28 will be quickly vaporized by contact with this warm air sweeping over it. The combustible mixture is initially ignited by the hot wire 36 and the flame is propagated through the mixture and discharged from the smaller end of the shell 28 into the combustion chamber formed by the inner sleeve or cylinder 26. At its opposite end the cylinder 26 is closed by an end wall, not shown.

The next adjacent sleeve or cylinder 54 is spaced from the sleeve 26 to form a passage 55 of annular cross section open from end to end for the flow of ventilating air to be heated. When the heater is installed in an automobile, a fan or blower, not shown, will usually be connected at one end or the other of the casing 10 to insure the flow of this ventilating air through the passage 55 and into the body of the vehicle for warming the driver's compartment, or the passenger space, or both. In the heater structure as shown, a third sleeve or cylinder 56 is spaced around the sleeve 54 and within the cylinder casing 10 in spaced relation to the latter so that a second annular passage 57 for ventilating air is provided between the casing 10 and the cylinder 56. The space 59 between the sleeves 54 and 56 is placed in communication with the combustion chamber to receive the products of combustion flowing therefrom and to distribute these hot gases over the surfaces of the sleeves 54 and 56 in heat exchange relation with the ventilating air flowing through the spaces 55 and 57. These hot gases are then conducted away through the exhaust pipe shown at 24.

The connection between the combustion chamber within the cylinder 26 and the space 59 is formed by a longitudinally extending slot 60 in the cylinder 26 which is disposed in registration with a similar longitudinal slot in the sleeve 54. As seen in Fig. 4, the material of the sleeve 54 which forms the margin of the slot 60 is offset inwardly at 62 by an amount equal to the radial width of the space 55, bringing this marginal area 62 into contact with the outer face of the cylinder 26. These contacting surfaces are electrically seam welded, thus forming a gas-tight joint between the two sleeves around the opening formed at the slot 60. This opening provides communication between the combustion chamber and the space 59 substantially throughout the length of the heater. Thus, the hot gases of combustion discharged from the burner space in the shell 28 toward the opposite end of the combustion chamber fill the chamber and then flow through the opening 60 and distribute themselves in both directions circumferentially through the space 59 toward the exhaust pipe 24 which, as shown, is disposed diametrically opposite the opening formed by the slot 60.

The sleeve 56 is spaced from the sleeve 54 by the provision of rings 63 to serve as end closures

for the space 59 formed between these two sleeves. As shown, these rings telescope within the respective end portions of the sleeve 56 as at 65 and are offset inwardly to fit snugly around the end portions of the sleeve 54 at 67 so that both joints may be conveniently made by seam welding, the rings being first welded to the ends of the sleeve 56 and then fitted over the end portions of the sleeve 54 and welded thereto. This provides a gas-tight connection between the sleeves 54 and 56 at both ends of the space 59. The outer casing 10 is preferably made in two parts connected by longitudinal lock seams 70 and 71 to facilitate assembly.

The automatic operation of the heater may be controlled by suitable devices arranged in an electrical circuit such as that shown and described in the previously referred to copending application.

In operation, the igniter is energized and the fuel is turned on either simultaneously or subsequently thereto, the fuel being delivered through the pipe 38. Customarily, this is accomplished by energizing a magnetic fuel valve in the line 38 at the same time the igniter is energized. Fuel flowing from the pipe 38 into the pocket 32 runs over and is heated by the hot shell 34 which in turn receives its heat from the glowing coil of wire 36. Although some of the fuel is vaporized by the hot shell 34, the major portion passes thereover and is absorbed by the wick 40 and after the wick has become substantially saturated the overflow passes along the floor of the chamber 32 into the bottom of the combustion chamber 28. At the time the heater is energized a combustion air blower starts delivering air through the pipe 14, 14a and elbow 14b so that the combustion air passes into the combustion chamber in a position between the end wall 30 and the baffle 50.

The fuel vapor which boils off the hot sleeve 34 is mixed with combustion air which eddies into the pocket 32 from the combustion chamber and the fuel and air mixture thus formed is ignited by the hot coil 36. This forms a small flame which ignites the mixture of fuel and air within the main combustion chamber almost immediately unless the temperature is extremely low in which case an appreciable interval of burning within the pocket 32 may take place before the combustion chamber is brought to such a temperature that combustion can be maintained therein. Once combustion is well established in the main combustion chamber, very little burning will continue to take place within the pocket 32 since the mixture therein will be too rich to burn. This is because as the pocket warms up, a larger portion of the fuel passing therethrough will be vaporized within the pocket while simultaneously, inasmuch as combustion is taking place within the main combustion chamber, there will be less oxygen in the gases by the time these gases reach the bottom of the combustion chamber where the opening to the pocket 32 is located.

Inasmuch as substantially all of the combustion takes place within the main combustion chamber the pocket 32 cools sufficiently to insure a long life for the igniter which is customarily de-energized as soon as combustion has been well established. During the period while combustion is taking place in the main chamber the major portion of the fuel flowing from the pipe 38 will pass across the bottom of the pocket 32 and into the main combustion chamber, the wick 40 helping to distribute the fuel somewhat

more evenly. The air sweeping over the liquid fuel at the lower side of the combustion chamber and mixing with some vaporized fuel issuing from the pocket 32 produces a mixture of fuel and air which burns with good efficiency and supplies hot gases to the heat exchange portion of the device. These hot products of combustion pass over the section 14a of the air pipe and raise its temperature, thereby preheating the combustion air. This is an aid in promoting stable and efficient operation of the device as well as enabling larger quantities of fuel to be burned within a combustion chamber of any particular size than would otherwise be practical.

While there is shown and described herein certain structure embodying the invention and illustrative thereof, it is to be understood that the invention is not limited thereto or thereby, but embraces all modifications, variations and equivalents thereof which come within the scope of the appended claims.

We claim:

1. In an internal combustion heater, a burner structure comprising a frusto-conical shell having a horizontal axis and open at its smaller end, a flat wall closing the larger end of said shell, a pocket in said wall opening into the lower portion of said shell, means to supply liquid fuel to said pocket, means to vaporize and ignite said fuel, a combustion air supply pipe discharging tangentially into the burner shell in a downward direction adjacent said flat end wall, and a vertical baffle wall extending across the lower portion of said shell in spaced relation to said end wall, the discharge end of said air supply pipe being between the end wall and the baffle wall, whereby the air flow is initially confined to the vicinity of said pocket opening to facilitate admixture of the air with the fuel.

2. In a heater as defined in claim 1, said air supply pipe comprising an elbow at its discharge end with a horizontally extending portion leading thereto through the upper portion of the burner shell in the path of the flame which

advances over said baffle wall and through the smaller end of the shell, whereby the incoming air is preheated.

3. In an internal combustion heater, a burner structure comprising a shell having a horizontal axis and open at one end, a wall closing the other end of said shell, a pocket in said wall opening toward the space in the shell, means for supplying combustion air into said space, a conduit for liquid fuel having a delivery outlet in the upper part of said pocket, an igniter which includes an internally heated tubular shell, said igniter being mounted in a vertical wall of said pocket with said tubular shell extending horizontally under said fuel delivery outlet for vaporizing the fuel as it strikes said heated shell, the bottom of the pocket sloping downwardly toward the opening which leads into the burner shell, an absorbent mat disposed beneath said tubular shell, and baffles extending inwardly from the side walls of the pocket engaging portions of said mat to retain it in the pocket but leaving space between them for drainage of liquid fuel over the sloping bottom into the burner shell.

GEORGE W. ALLEN.
VERNON N. TRAMONTINI.
